UNITED STATES PATENT OFFICE.

CLAYTON N. DAVIS, OF FORT EDWARD, NEW YORK, ASSIGNOR TO RUSSELL C. DAVIS AND H. DAVIS NORTHUP, OF SAME PLACE.

SHIRT.

SPECIFICATION forming part of Letters Patent No. 274,919, dated April 3, 1883.

Application filed December 9, 1882. (No model.)

To all whom it may concern:

Be it known that I, CLAYTON N. DAVIS, a citizen of the United States, residing at Fort Edward, in the county of Washington and State of New York, have invented a new and useful Improvement in Shirts, of which the following is a specification.

My invention relates to improvements in the method of re-enforcing the back of a shirt and concealing the opening therein; and it consists of a re-enforcing ply stitched to the body of the shirt on both its vertically-inclined sides and bottom, being open at the top, and adapted to button at its upper side to the yoke of the shirt.

The objects of my invention are, first, to conceal the back opening or slit; second, to re-enforce the back by an additional ply or thickness of cloth. I attain these objects by constructing the shirt in the manner illustrated in the accompanying drawing, in which the figure is a view of the back of a shirt, showing the covering and re-enforcing ply A.

The broken line *a b* represents the position of the opening or slit in the back of the shirt, and A the covering and re-enforcing ply. The button E serves to hold together the ends of the neckband, and the button D the ends of the yoke C, and also to secure the upper side of the ply A when buttoned thereon. The dotted lines represent rows of stitching, and the ply A is stitched to the body of the shirt from F to G at the bottom and from G to F' on the other side. From F' to D and from D to F the fly is left loose. When the respective parts are released from the buttons the shirt can be opened sufficiently to be easily put on or removed from the wearer. The ply A may be stitched with one or more rows of stitching across the lower part, just below the opening, as shown.

The facing of the upper side of ply A may be extended and stitched to the body of the shirt on each side—as, for example, to B and B'—which serves to relieve the corners F and F' from the strain occasioned by a forward

movement of the shoulders. By stitching the covering-ply to the body of the shirt upon both sides of the opening, and then buttoning the upper side to the yoke, the perfect concealment of the opening is rendered certain.

The covering-ply A may be of one or any desired number of thicknesses and of any suitable material, and may be of any desired shape, provided it is stitched to the body of the shirt on both sides of the back-opening, as described. The sides of the ply A may extend upward to and be stitched as far as the yoke to the body of the shirt, having the upper loose sides straight or nearly straight across from one stitched side to the other, and adapted to button upon the yoke-button, as described. The facing on the flap or loose side of ply A extends, as described, beyond the ply A. The extensions may be split, and one branch extended upon and stitched to the body of the shirt, as shown at B and B', while the other branch is carried back under the facing on the edge of the flap, and stitched to the body of the shirt between the points F and F' and the yoke. The extensions need not necessarily be a part of the facing, and may be of any suitable material.

What I claim as new, and desire to secure by Letters Patent, is—

1. In a shirt, a covering or re-enforcing ply stitched to the body of the shirt on both of its inclined sides and bottom, and unstitched at the top end, but provided with a button-hole, so as to be buttoned to the yoke or collar band of the shirt, substantially as described, and for the purpose set forth.

2. In a shirt, the covering-ply A, stitched to the body of the shirt on both sides of the back-opening, in combination with the extensions B and B', also stitched to the body of the shirt, substantially as described, and for the purposes mentioned.

CLAYTON N. DAVIS.
